HEATING PAD

Abe O. Samuels, Bridgeport, Conn., assignor to
 Casco Products Corporation, Bridgeport, Conn.,
 a corporation of Connecticut

Application April 2, 1947, Serial No. 738,839

3 Claims. (Cl. 128—254)

1

This invention relates to electric heating pads.

An object of the invention is to provide a flexible therapeutic electric heating pad which may be conveniently secured and held in place on various areas of the body of a user, and which may be readily cleaned and sterilized when soiled.

Another object of the invention is to provide a pad as above used which, in addition to its capacity for applying a dry heat, is so organized that moist or wet heat may be advantageously applied without leaking or spilling of the fluid, or without requiring frequent renewal of the fluid.

A further object of the invention is to provide a heating pad having all of the above characteristics, together with high thermal efficiency and choice of heats whereby both wet and dry treatments may be administered with maximum effectiveness and benefit.

Still another object of the invention is to provide a heating pad according to the foregoing, which is entirely safe in use.

A still further object of the invention is to provide a heating pad applicable to various surfaces of the body for prolonged application of heat, and which enables the user to have considerable freedom of movement and to move about within a predetermined area, insofar as the pad is concerned.

A feature of the invention is the provision of a flexible, lightweight, completely wet-proof heating pad of high thermal efficiency, which also has high mechanical strength and resistance to undesirable deformation or distortion.

A further object of the invention is to provide a heating pad as above, which is economical to fabricate.

These and other objects are accomplished, according to the invention, by an organization including a completely wetproof, flexible heating pad and fabric slip cover, the latter having a pocket arranged to receive the pad, and having substantially coextensive with said pocket and superposed thereon, a second pocket or recess into which a moisture reservoir in the form of a moistened sheet may be inserted. Tie strings are provided for use with this assemblage, so arranged as to enable the assemblage to be conveniently fastened over the desired area of the user's body and securely held in place.

The fabric slip cover and tie strings are readily separable from the heating pad unit, and therefore may be repeatedly easily washed and laundered, and otherwise sterilized, and since the pad unit itself is completely wetproof and has readily accessible exposed surfaces, it also may be

2

washed and sterilized. As a consequence, the heating pad assemblage as provided herein is extremely sanitary in all respects.

The moisture reservoir sheet has spongelike characteristics and is so constructed and related to the slip cover and heating pad unit that no leaking or dripping of fluid occurs during use of the pad, and that sufficient moisture is retained for effective treatment over a period of as much as twelve hours, and thus is of considerable advantage in reducing the attention required of trained attendants, for example.

In one embodiment of the invention an applicator sheet is provided, by which salves, ointments and the like may be applied, the said sheet being readily detachable from the slip cover body and replaceable by a fresh sheet, and being so arranged as to form the means for holding in place the moisture reservoir sheet.

In another embodiment of the invention where-in the pad unit is narrow and elongate in configuration, the thermostatic control means, which have appreciable bulk, are located adjacent the extremities of the pad so as to interfere to the least extent and provide for the maximum possible comfort when the pad is in use, and condensers associated with the said means are included in the housings therefor, eliminating extra bulk.

30 By virtue of a unique and novel electrical pad construction involving rubberized fabric foundation and envelope sheets, a highly efficient heat transmission is effected from the coils to the outside of the pad, increasing thermal efficiency and 35 reducing the maximum internal pad temperatures which are required, while at the same time high mechanical strength and resistance to undesired distortion is retained.

The method of securing the pad assemblage to 40 the body of a user by positive-holding tie strings enables a maximum freedom of movement to be had, so that the user need not be immobilized on account of the pad.

45 Other features and advantages will hereinafter appear.

In the accompanying drawings:

Figure 1 is a perspective view showing the improved heating pad and slip cover assemblage as provided by the invention, the heating pad being 50 not quite completely inserted in the slip cover.

Fig. 2 is a top plan view of the heating coils of the pad secured to the rubberized textile fabric base or foundation.

55 Fig. 3 is a plan view of the heating coil and

foundation assemblage, having secured to it the thick sheet of heat-insulating material.

Fig. 4 is a plan view of the assemblage of Fig. 3 enclosed in an outer water-proof envelope of rubberized textile fabric.

Fig. 5 is a transverse section taken on the line 5—5 of Fig. 3.

Fig. 6 is a transverse section taken on the line 6—6 of Fig. 4.

Fig. 7 is a transverse section taken on the line 7—7 of Fig. 1.

Fig. 8 is a perspective view of a slip cover made according to a modification of the invention.

Fig. 9 is a perspective view of a larger size heating pad, illustrating also another modification of the invention.

Fig. 10 is a plan view of one of the thermostatic controls, with cover removed, of the pad of Figs. 1 through 7, and

Fig. 11 is a schematic wiring diagram of the heating pad.

As shown the improved heating pad of the present invention comprises a heating element 10 formed of the usual spirally wrapped heating element wire 11 which is disposed in flat convolutions and sewed to a flexible base or foundation sheet 12.

The foundation sheet 12 is of fabric, and may be formed of rubberized fabric which, while being thoroughly impregnated with the rubberizing compound, is of the type formed by rubberizing one side thereof. If the foundation sheet 12 is of rubberized fabric, the convolutions of heating element wire 11 are preferably sewed to the side of the foundation sheet 12 which has not been rubberized. However, although this side of the sheet has not been rubberized, actually the rubberizing compound exists throughout the sheet and therefore comes in intimate contact with the heating element wire 11.

As shown in Figs. 2 and 11, for the purpose of controlling the operating temperature of the heating element and also to provide a safety factor, thermostats 13 and 13a are included in series with the heating element 10 and are secured by stitches 14 over the opposite ends of the heating coil assemblage. The thermostats 13 and 13a are connected together in series by a wire 15, one thermostat being connected by a second wire 16 to one conductor of a rubber-covered supply cord 17 the other conductor of which is connected with an end of the heating element 10.

According to the invention a relatively thick sheet 18 of heat-insulating material is placed over the convolutions of the heating element 10 and secured along its marginal portions to the marginal portions of the foundation sheet 12 by stitches 19. The sheet 18 of heat insulation, together with the rubberized foundation sheet 12 thus form a flat bag or envelope which completely encloses the heating element 10 and prevents rumpling of the sheet 18 and preferably the rubber-covered electric cord 17 is brought out through one corner of the bag as shown in Fig. 3.

The assemblage of Fig. 3 is enclosed in an outer bag or envelope 20, shown in Fig. 4, which latter is also formed of rubberized textile fabric preferably with the rubberized side out. The marginal portions of the outer envelope 20 may be sealed in any suitable manner as by applying an adhesive compound 21 thereto and vulcanizing the portions together. During such operation the corner portion 22 of the outer envelope is also vulcanized to the rubber-covered electric

cord 17, thereby producing a completely water-tight and air-tight, sealed unit.

Referring to Fig. 6, it will be seen that the heating element wires 11 are directly in contact with the rubberized foundation sheet 12 and heat the latter to a high temperature, not only by conduction but also by radiation. Also, the rubberized foundation sheet 12 is adapted to engage the rubberized side 23 of the outer envelope and heat the latter both by conduction and radiation. As a consequence, since the rubberized fabrics are relatively good conductors of heat as compared with untreated textile fabrics which have numerous interstices filled with air, heat from the heating element 10 will be efficiently conducted to the exterior surface of the side 23 of the outer envelope, and will heat this side to a relatively high temperature. Due to the efficiency of the heat transmission to the exterior surface of the side 23, the heating element 10 may be maintained at a relatively low temperature and still produce a predetermined effective high temperature in the side 23 of the outer envelope.

Considering the opposite side 24 of the outer envelope, it will be observed that there is interposed between this latter side and the heating element 10 the relatively thick sheet of heat insulation 18. This sheet may be formed of any suitable material having cotton and woolen fibres in varying proportions, and preferably has large, trapped air spaces which act as heat insulators. As a consequence, the temperature to which the side 24 of the outer envelope will be heated is considerably lower than the temperature to which the side 23 is heated. This latter side is thus termed the "high" side of the heating pad, and the side 24 the "low" side.

In accordance with the invention, for the purpose of enabling the pad structure above to be used in conveniently applying a hot wet compress to various different affected parts of the body to be treated, thus to employ the principle of fomentation, a sanitary washable fabric slip cover 25 is provided, having a pocket 26 open at opposite ends into which the heating pad may be longitudinally inserted, and having a second pocket 27 open along a longitudinal edge of the slip cover for receiving a fomentation or moisture-carrying sheet 28.

The heating pad may be inserted in the slip cover 25 so that either its "high" or its "low" side is adjacent the fomentation pad 28, and thus either a high or low heat may be applied to the said pad, for transmission to the afflicted part of the body. Or, if desired, the dry side 29 of the slip cover may be applied to the body and may have either a high or a low heat transmitted to it by changing the position of the heating pad 60 within the slip cover.

As shown in Fig. 1 the heating pad is not quite completely inserted in the slip cover. When it is fully inserted by shifting it to the right into the slip cover, the ends of the pad and cover will be closely adjacent each other and the supply cord or lead wires 17 will project from the end of the slip cover. The ends of the slip cover 25 are folded to form V-shaped extensions 30, and tie-strings 31 are secured to the extensions to project from the pointed ends thereof. Preferably the tie-strings 31 and extensions 30 are secured together by rows of stitches 32 which provide a secure anchorage for the strings. By this organization the heating pad of the present invention and fomentation pad 28 may be quickly

and conveniently applied to various parts of the body. For example, the slip cover 25 having the said pads may be secured over the forehead, and tied behind the head by the strings 31, and either the fomentation pad 28 or the heating pad may be placed nearest the skin. Also, the slip cover may be readily tied about an arm or leg or other part of the body, wherever wet or dry heat is desired.

It will be seen that the heating pad described above is of extremely simple construction. Through actual test it has been found that the use of a rubberized fabric foundation sheet, together with a rubberized outer envelope in intimate heat-conducting relation with the foundation, produces a pad having a high thermal efficiency thereby enabling the internal temperatures of the pad to be lowered, while still producing a given external temperature. The heating of the element 10 is not so great as to adversely affect the strength or water-proof properties of the rubberized fabrics used, and it has been found that the resistance to water of the said fabrics increases rather than decreases after the application of heat, and also upon aging.

The amount of rubber used in the entire pad is extremely small, and since rubber is an expensive material as compared with textile fabrics and the like, the cost of material entering into the pad is kept at a low figure. Also, the pad is of extremely light weight, which is of considerable advantage in many instances.

By the rubberized fabric construction as described above, a pad is produced which is extremely flexible, and yet has a high mechanical strength and is resistant to severe usage under adverse conditions. The pad is not easily deformed nor distorted, and therefore damage or malfunctioning of the heating element is avoided.

It will be noted that the base or foundation sheet 12 also functions as a distributor of heat from the heating element 10. The sheet 12 receives the heat from the element 10 by conduction through direct contact therewith, and also by direct radiation therefrom. In consequence of this, the foundation sheet 12 becomes substantially uniformly heated throughout its area and this heat is then transmitted to the rubberized wall 23 of the outer envelope so as to uniformly heat the said wall.

By virtue of the fact that the rubberized side of the foundation sheet 12 is the side which is in contact with the wall 23 of the outer envelope, a high transmission of heat is obtained which is better than if the rubberized side of the foundation sheet were to be oppositely located, in contact with the heating wires 11.

Referring to Fig. 6, it will be seen that the foundation sheet 12 also acts as a pad between the heating element wires 11 and the wall 23 of the outer envelope, and tends to prevent the wires from being easily felt or distinguished from one another through the envelope.

A slip cover 33 illustrating a modification of the invention is shown on Fig. 8. The slip cover 33 comprises an elongate flat tubular body 34 having squared ends and being preferably open at both ends, whereby the heating pad unit may be easily and quickly fully inserted.

Along the central portion of one side 35 of the body 34 a fabric tape 36 is sewed, the ends of the tape being extended beyond the slip cover body and functioning as the tie strings. By this construction there is obviated the possibility that strong opposed pulls on the ends of the tape

will tend to separate it from the body 34 of the slip cover.

A pocket for receiving the fomentation pad 28 is formed by sewing to the opposite side 37 of the tubular body 34 three edges of a fabric sheet or panel 38 the fourth edge 39 of which is free of the side 37 so that a pocket is thereby formed. Preferably, as shown, the longitudinal edge 39 of the sheet 38 is spaced inward a small distance from the adjacent longitudinal edge of the body 34, thereby providing for more convenient insertion of the fomentation pad 28 since it is possible to more easily initially separate the said spaced longitudinal edges.

A heating pad 40 illustrating another modification of the invention is shown in Fig. 9. This pad comprises a slip cover of rectangular and almost square configuration, in the form of a flat bag having sides 41 and 42 joined together along three edges 43, 44 and 45, leaving an open mouth 46 through which the flexible heating pad unit 47 is inserted. Rows of stitches 48 are provided, extending parallel with and spaced from the edges 43 and 45 to form flat marginal portions along said edges, and in one marginal portion button holes 49 are provided through which tie strings 50 may be passed.

At the mouth 46 of the slip cover the sides 41 and 42 thereof are provided with cooperable snap fasteners 51 by which the pad unit 47 may be retained in the cover.

For the purpose of holding a fomentation pad 52 to the side 42 of the slip cover, and to enable salves and other medication to be applied in a sanitary and convenient manner, an applicator sheet 53 which is preferably of cotton flannel is provided, said sheet having snap fasteners 54 cooperable with mating fasteners secured to the flat marginal portions of the slip cover. The applicator sheet 53 and side 42 of the slip cover form a pocket 55 into which the fomentation pad 52 may be readily inserted, and from which it can be easily removed.

By use of the snap fasteners 54 the applicator sheet 53 may be easily replaced, so that soiled applicator sheets may be conveniently cleaned as by laundering, and maintained in a sanitary condition.

The heating pad 40 may be easily applied and held to many different afflicted parts of the body 50 by virtue of its complete flexibility and by the provision of the tie springs 50, and may be used to produce either dry or wet heat, as desired. Where a slim member such as a forearm is wrapped with the pad 40, the edges of the pad 55 may be overlapped and yet permit the pad to be tied in place by the strings 50 since the latter pass through only one of the flat marginal portions of the slip cover. Due to the removability of the applicator sheet 53 from the slip cover, and of the pad unit 47 from the slip cover, complete cleaning and sterilizing of the entire heating pad is easily accomplished, including laundering of the applicator sheet and slip cover.

In accordance with the invention a novel, simple and compact means is provided whereby the tendency of the thermostats 13 and 13a, when operating, to interfere with radio reception is minimized. Referring to Fig. 10, the thermostat 13 is provided with a small cylindrical condenser 55a having one end 56 connected with the thermostat terminal 57, and having the other end 58 connected with a condenser terminal 59 on the thermostat housing 60. As seen in Fig. 11 the condenser terminal of the thermostat 13 is

connected by a wire 61 to the terminal 57 of the thermostat 13a whereby the condenser 55a is made to bridge the series-connected thermostats; thus surges due to arcing or sparking which occurs during operation of the thermostats are by-passed through the condenser and prevented from passing out into the supply line. The condenser 55a is small enough to be completely housed in the housing 60 of the thermostat 13, and the circuit and organization is such that no additional space whatsoever in the heating pad unit is required. This is of considerable importance where a heating pad is intended for use in the manner of a wrapping around a part of a user's body.

Referring to Fig. 2 the thermostats 13 and 13a are located adjacent opposite ends of the heating pad unit where I have found their bulk to be least objectionable, thereby providing for a maximum of comfort on the part of a user.

Variations and modifications may be made within the scope of this invention and portions of the improvements may be used without others.

I claim:

1. The combination of an elongate heating pad of generally rectangular configuration, having lead wires extending from one end thereof; a rectangular fomentation pad; and a rectangular slip cover having separate pockets respectively carrying said heating pad and fomentation pad in superposed relationship, said pads being substantially co-extensive with each other, one of said pockets having a mouth extending along a longitudinal edge of the slip cover and the other pocket having a mouth located at one end of the slip cover, and said lead wires projecting from an end of the slip cover; and means secured to the ends of the slip cover for securing the same to the body of a user.

2. A therapeutic device comprising the combination of an electric heating pad; a fomentation pad; a slip cover for use with said pads to secure the same to the body of a wearer, said slip cover having a pair of pockets superposed on and substantially coextensive with each other, carrying respectively the heating pad and fomen-

tation pad, one of said pockets having a mouth extending along one edge of the slip cover and the other pocket having a mouth extending along a different edge of the slip cover connecting with said first edge, said mouths admitting said pads during assembly of the device; and means for securing the slip cover to the body of a user.

3. A therapeutic device comprising the combination of an electric heating pad; a fomentation pad; a rectangular slip cover for use with said pads to secure the same to the body of a wearer, said slip cover having a pair of pockets superposed on and substantially co-extensive with each other, carrying respectively the heating and fomentation pads, said fomentation pad pocket having a mouth extending along a longitudinal edge of the slip cover and the other pocket having a mouth located at one end of the slip cover, said mouths admitting said pads during assembly of the device; and means located at the ends of the slip cover for securing the same to the body of the user.
